UNITED STATES PATENT OFFICE.

LESTER R. NICHOLS AND ELMER H. NICHOLS, OF STRAWBERRY POINT, IOWA.

PACKAGE-ENVELOP.

1,205,250.

Specification of Letters Patent. Patented Nov. 21, 1916.

Application filed February 9, 1916. Serial No. 77,177.

To all whom it may concern:

Be it known that we, LESTER R. NICHOLS and ELMER H. NICHOLS, citizens of the United States, residing at Strawberry Point, 5 in the county of Clayton, State of Iowa, have invented a new and useful Package-Envelop; and we do hereby declare the following to be a full, clear, and exact description of the invention, such as will enable others skilled in the art to which it appertains to make and use the same.

The present invention relates to a combined envelop and address card for packages, and has for its object to provide a device of this character embodying novel features of construction whereby a letter or other papers may be inclosed in a sealed envelop which is adapted to be secured to a package accompanying the letter with the 20 address card for the package, so as to insure the delivery of the letter and package at the same time.

Further objects of the invention are to provide a device of the character described 25 which can be utilized to insure the delivery of the letter with the package when the same is sent by either a special messenger or through the mails.

Further objects of the invention are to 30 provide a device of the character described which is simple and inexpensive in its construction and which can be easily and quickly secured to a package of any description.

With these and other objects in view, the 35 invention consists in certain novel combinations and arrangements of the parts as will more fully appear as the description proceeds, the novel features thereof being 40 pointed out in the appended claim.

For a full understanding of the invention, reference is to be had to the following description and accompanying drawing, in which:—

45 Figure 1 is a plan view of the back of the blank from which the combination envelop and address card is constructed. Fig. 2 is a similar view showing the first step in the folding of the envelop. Fig. 3 is a similar 50 view showing the second step in the folding of the envelop. Fig. 4 is a plan view of the back of the combined envelop and address card with the envelop completed and sealed. Fig. 5 is an enlarged longitudinal sectional 55 view through the device showing the same as applied to one side of a package. Fig. 6 is

a plan view of the front of the device. Fig. 7 is a fragmentary plan view of the front of a modified form of the invention.

Corresponding and like parts are referred 60 to in the following description and indicated in all the views of the drawing by the same reference characters.

Specifically describing the present embodiment of the invention, the numeral 1 65 designates the blank from which the device is constructed, the said blank consisting of a sheet of any desirable material, but preferably paper or cardboard, one end 1^a thereof serving to form the envelop while 70 the other end 1^b serves as the address card for the package. The blank 1 is provided at a short distance from one end thereof with a pair of laterally projecting and oppositely extending wings 2, the said wings 2 75 projecting from opposite sides of the main body portion of the blank 1, and being adapted to be folded upwardly along the lines 3 at the edges of the blank 1, so as to form the end flaps of the envelop, as shown 80 by Fig. 3. One of these wings or flaps 2 is provided at its outer edge with a strip of adhesive 2^a which serves to secure the flaps of the envelop together when folded. Each of 85 these wings 2 is slotted at 4 for a portion of its length, the said slits extending in alinement with the edges of the blank 1. These slits 4 provide supplemental flaps 5 along one side of the wings 2, the said flaps 5 being adapted to be folded upwardly along 90 the lines 6, as shown by Fig. 2. Each of these flaps 5 is provided upon its reverse side with a strip of adhesive 5^a to securely fasten them to the blank 1 when the envelop is folded. The end 7 of the blank 1 nearest 95 the wings 2 is adapted to be folded upwardly along the line 8 so as to form a sealing flap for the envelop, the said flap being provided with an adhesive 7^a to securely seal the envelop.

When folding the envelop from the blank, the supplemental flaps 5 are folded upwardly along the lines 6, as shown by Fig. 2, after which the wings or flaps 2 are folded upwardly along the lines 3, as shown by Fig. 3, the flap 2 carrying the adhesive 2^a overlapping the other flap 2, as shown by Fig. 3. The adhesive 2^a and 5^a upon the flap 2 and supplemental flaps 5 respectively, is then moistened, after which the flaps 2 and supplemental flaps 5 are pressed downwardly upon the body portion of the blank 1. The

flaps 5 will adhere to the blank 1 and the adhesive upon the flap 2 will secure the edges of the flaps 2 together.

It will thus be seen that a complete envelop is provided, the folding of the flaps 5 and securing them to the back of the blank 1 forming the bottom edge of the envelop, while the folding of the wings 2 forms the ends and back of the envelop, the front of the envelop being formed by the portion 1^a of the blank 1. In order to seal the envelop it is merely necessary to moisten the adhesive 7^a upon the flap 7 and fold the flap over the end flaps 2 of the envelop, as shown by Fig. 4.

It will be noted that the envelop is formed upon the back side of the blank 1. The front side of the blank 1 is utilized for the addresses, directions, and postage, and serves as the face of both the envelop and address card. The front side of the blank is divided into two spaces 9 and 10 which may be separated by an ink line or, if it should be desirable to have the envelop and address card for the package readily detachable, a line of perforations may be provided. The space 9 is formed upon the portion 1^a of the blank upon which the envelop is formed and serves as the front of the envelop. If desired, lines 9^a may be provided for the name and location of the addressee and lines 9^b for the return card of the sender, one corner 9^c of the space being reserved for postage stamps. The other space 10 is adapted to be utilized as the address card for the package, and may be divided similarly to the space 9, lines 10^a being provided for the name and location of the addressee, and lines 10^b for the return card of the sender, the space 10^c being reserved for postage stamps.

When it is desired to send a letter to accompany a package, the letter is inserted in the envelop and the envelop sealed. The back of the device is then completely covered with an adhesive and the device applied to one side of the package, as shown by Fig. 5, the whole device then readily adhering and being secured to the package. The proper inscriptions can then be made upon the front of the device after which the package may be shipped, the simultaneous delivery of the letter in the envelop and the package being then assured.

Should it be desirable to quickly and

neatly detach the envelop from the address card upon the package, a line of perforations 11 may be provided between the address card and envelop, as shown by Fig. 7, and when applying the device to a package the adhesive could be applied only to the address card. The envelop could then be easily and neatly detached without mutilation by tearing along the line of perforations, the address card remaining on the package.

Having thus described the invention, what we claim as new and desire to secure by Letters Patent, is:—

A device of the character described including a single elongated piece of sheet material provided near one end thereof with a pair of laterally and oppositely extending wings projecting from the longitudinal edges of the main body portion of the piece of material, and adapted to fold over upon one side of the main body portion to form the end flaps of an envelop, a pair of corresponding supplemental wings formed upon the longitudinal edges of the said laterally extending wings, said supplemental wings being provided with an adhesive and being adapted to adhere to the main body portion to form the bottom edge of the envelop when the laterally projecting wings are folded upon the main body portion, and the end of the body portion adjacent the laterally extending wings being adapted to serve as a sealing flap for the envelop, while the opposite end of the body portion is adapted to serve as an address card, the side of the body portion opposite that upon which the envelop is folded forming a continuous surface serving as the front of both the envelop and the address card and that portion serving as the front of the envelop being adapted to receive the name and address of the addressee for the envelop, while that portion serving as the front of the address card is adapted to receive the name and address of the consignee for the package.

In testimony whereof we have signed our names to this specification in the presence of two subscribing witnesses.

LESTER R. NICHOLS.
ELMER H. NICHOLS.
